US00D707813S

(12) **United States Design Patent**
Dobrin et al.

(10) **Patent No.:** **US D707,813 S**
(45) **Date of Patent:** **** Jun. 24, 2014**

(54) **ABSORBENT ARTICLE WITH A PATTERN**

(71) Applicant: **The Procter & Gamble Company**,
Cincinnati, OH (US)

(72) Inventors: **George Christopher Dobrin**, Mason,
OH (US); **Beth Goldman Mason**,
Cincinnati, OH (US); **Daniel Patrick**
Findley, Finneytown, OH (US);
Timothy Wayne Robertson, Cincinnati,
OH (US); **David Rex Price**,
Indianapolis, IN (US)

(73) Assignee: **The Procter & Gamble Company**,
Cincinnati, OH (US)

(**) Term: **14 Years**

(21) Appl. No.: **29/478,589**

(22) Filed: **Jan. 7, 2014**

Whitmer

(57) **CLAIM**

The ornamental design for an absorbent article with a pattern,
as shown and described.

DESCRIPTION

FIG. 1 is an enlarged, partial development view of the claimed
left portion of a first embodiment of an absorbent article with
a pattern seen in its entirety in FIG. 3;
FIG. 2 is an enlarged, partial development view of the claimed
right portion of the first embodiment of an absorbent article
with a pattern seen in its entirety in FIG. 3;
FIG. 3 is a development view of the first embodiment of the
absorbent article with a pattern;
FIG. 4 is an enlarged, partial development view of the claimed
left portion of the second embodiment of an absorbent article
with a pattern seen in its entirety in FIG. 6;
FIG. 5 is an enlarged, partial development view of the claimed
right portion of the second embodiment of an absorbent
article with a pattern seen in its entirety in FIG. 6; and,
FIG. 6 is a development view of the second embodiment of
the absorbent article with a pattern.

The broken lines, including those showing the diaper tabs and
ears, are included for the purpose of illustrating environment
and form no part of the claimed design.

1 Claim, 2 Drawing Sheets
